UNITED STATES PATENT OFFICE

2,401,960

PRESSURE DRILLING HEAD

Albert Pranger, Dallas, Tex., assignor to The
Guiberson Corporation, Dallas, Tex., a corpora-
tion of Delaware

Application May 15, 1942, Serial No. 443,087

3 Claims. (Cl. 255—19)

1

This invention relates to an improvement in pressure drilling heads. More specifically it consists of an improvement over that type of drilling head shown in the patent granted to Albert Pranger and Samuel Allen Guiberson III, 2,243,439, issued May 27, 1941. In the said patent the lower end of the corrugated packer was subjected to well pressures. The upper end of the packer could be pushed downwardly so as to compress the packer by rotating the nuts on the bolts 19. In the structure shown in the said patent the gland 9 operated in opposition to the pressures in the well, and it was therefore frequently difficult to operate the said bolts so as to move the gland downwardly. In my improved construction I provide a drawing means which may be manually operated but which exerts a force on the lower end of the packer to compress the same. In my improved construction, shown by way of illustration in the attached drawings, I have therefore provided a drawing means which acts in conjunction with the well pressures to compress the packer.

Another object of the invention is to provide a packing mechanism rotatable with the kelly in a fixed housing, which packing means may be disengaged from the fixed housing so that the drill bit may be removed from the well without removing the fixed housing and without the necessity of removing a rotatable housing within the fixed housing and the antifriction bearings between the fixed and the rotatable housings. In the said Patent 2,243,439 it would of course be possible to loosen the nuts on the bolts 19 and thereupon the packer could be removed from the sleeve or rotatable housing 13, but as soon as it was removed, the packer would expand radially, and it would be very difficult to reinsert the packer while on the kelly or drill pipe within the rotatable housing 13. In my preferred construction I provide a sleeve which serves as a confining means for the packer and which sleeve and packer may be removed from the rotatable housing without disturbing the rotatable housing and the various sealing means, antifriction bearings and oil reservoirs between rotatable housing and the fixed housing. When thus removed the confining sleeve holds the packer against lateral displacement. The said sleeve can then readily be reinserted in the rotatable housing without disturbing the packing arrangement.

Other objects and advantages of the invention will appear in the detailed specification and claims which follow. The invention may be better understood by referring to the attached draw-

ings in which I have shown by way of illustration one preferred embodiment of the invention and in which,

Figure 1 is a vertical, cross-sectional view of my improved pressure drilling head, a square kelly being shown in conjunction therewith, and

Figure 2 is a view similar to Figure 1, but showing the removable packing mechanism lifted above the parts which are not to be removed, a round drill pipe being shown in conjunction therewith.

In the drawings a fixed housing 1 is attached to the well head by bolts 2. Secured to the top of the fixed housing 1 is a flange 3 which is secured thereto by bolts 4. The bolts 4 are screwed in the upper end of the fixed housing 1 and nuts 5 overlie the flange 3. The flange 3 is provided with upwardly extending circular rims 6 and 7.

A rotatable housing 8 is mounted within the fixed housing 1. It is provided with a shoulder 9. Antifriction roller bearings 10 are interposed between a bearing plate 11, which underlies the flange 3, and a bearing plate 12, which overlies the shoulder 9. Obviously, this roller bearing would prevent an upward vertical thrust of the rotatable housing 8. The rotatable housing 8 is also provided with a shoulder 13, which overlies a bearing plate 14. The fixed housing 1 is provided with a bearing plate 15. Interposed between the bearing plates 14 and 15 are antifriction rollers 16. These rollers have an axis which extends at an angle to the vertical, as well as the horizontal, directions so as to take a thrust in both directions. There is, therefore, provided a means to prevent the rotatable housing 8 from moving upwardly or downwardly as well as laterally of the fixed housing 1. An oil chamber 17 lies between the fixed housing and the rotatable housing, and a seal ring 18 is interposed between the lower skirt 19, forming a part of the rotatable housing, and a flange 20 forming a part of the fixed housing. Packing 21 is also provided between the fixed and the rotatable housings below the flange 20, and a rotatable gland 22 is screw threaded to the fixed housing 1 and serves as a means to compress the packing 21. The packing 21 serves as a means to prevent the well fluids from passing upwardly between the fixed and the rotatable housings. A bearing ring 23 is interposed between the rim 6 and rotatable housing, which bearing ring is preferably made of antifriction metal.

Secured to the upper end of the rotatable housing 8 is a ring 24 having depending flanges 25 and 26, the depending flange 25 resting between

the rims 6 and 7, and the flange 26 lying outside of the rim 7. The purpose of these flanges 25 and 26 and rims 6 and 7 is to tend to prevent dirt and other foreign matter from reaching the bearing ring 23.

A sleeve 27 fits within the rotatable housing 8 and rotates therewith, but is vertically removable therefrom. The sleeve 27 is provided with an inwardly extending flange 28 which underlies and supports a ring 29 on which is seated the lower end of a packer 30. The packer 30 is shown as corrugated, and as fully explained in the said Patent 2,243,439, such a packer is suitable to pack off around a square kelly 31 shown in Figure 1, or a round kelly or drill pipe 32, as shown in Figure 2.

The lower end of the flange 28 lies slightly above a shoulder 33 of the rotatable housing 8, and a sealing ring 34 is interposed within the circular channel of the sleeve 27. It will be noted from inspecting Figure 1 that this sealing ring will be expanded by well pressures so as to make an effective seal between the sleeve 27 and the rotatable housing 8.

The upper end of the sleeve 27 is provided with a flange 35 which overlies the upper end of the rotatable housing and, therefore, serves as a stop to limit the downward movement of the sleeve 27 relative to the rotatable housing. Bolts 36 are screwed into the flange 35 and pass upwardly through an unthreaded hole 37 in the gland 38. Nuts 39 are screwed onto the threads of the bolts 36 and these nuts overlie the top of the gland 38. A rotatable retaining ring 40 is screwed to the upper portion of the ring 24 and serves as a means to secure the gland 38 to the ring 24 which, it will be remembered, is secured to the rotatable housing 8. One or more keys 41 pass through holes or slots in the ring 24 and into slots of the gland 38. It is, therefore, obvious that the gland 38, ring 24, rotatable housing 8, sleeve 27 and packer 30 all rotate as a unit with the kelly 31. If desired, however, the gland 38 may be provided with a vertically extending keyway 42, and a key 43 may extend into this keyway and be secured to the upper end of the sleeve 27 by means of a bolt 44. Ordinarily it is not necessary to interpose any member, such as a kelly clamp 2 and 3 of the said Patent 2,243,439, between the kelly and the gland 38, for the packer 30 serves as a means to transmit the rotation from the kelly 31 to the parts which rotate therewith. It is furthermore obvious that before the packer is subjected to well pressures, when for instance it is in the position shown in Figure 2, the nuts 39 can be tightened on the bolts 36 to compress the packer by pushing downwardly on the gland 38 and pulling upwardly on the sleeve 27 which carries its flange 28, so that the upper end of the packer would be pushed downwardly and the lower end of the packer would be moved upwardly. When, however, the packer is subjected to well pressures, these well pressures would be exerted against the lower end of the packer which would tend to move the lower end of the packer upwardly, while the retaining ring 40 prevents any movement of the gland 38. If now the nuts 39 were rotated so as to move the sleeve 27 upwardly, it would further compress the packer so that the drawing means acts in conjunction with the well pressures to compress the packer, in contradistinction to the structure shown in the said Patent 2,243,439, in which the

drawing means acted in opposition to the well pressures.

In the drilling of oil wells, it is necessary to remove the bit from time to time. This necessitates the pulling from the well of the kelly and the drill pipe. In the structure shown in the said Patent 2,243,439 this could be done, and after the conventional gate valve had been closed after the drill had passed above it, the entire pressure drilling head including the fixed housing could be removed. To remove the entire assembly, however, is objectionable. In my improved construction shown in this application, if the operator loosens the retaining ring 40, the gland 38, sleeve 27 and packer 30 may be removed as is shown in Figure 2, the said sleeve 27 simply moving vertically out of the rotatable housing 8 while the packer 30 remains compressed around the kelly or drill pipe. When it is desired to reinsert the removable assembly, it can again be lowered so that the sleeve 27 moves downwardly in the rotatable housing 8.

I realize that many changes may be made in the specific form of the invention shown by way of illustration herein, and I therefore desire to claim the same broadly, except as I may limit myself in the appended claims.

Having now described my invention, I claim:

1. A pressure drilling head of the type adapted to receive a rotary kelly and including a packer, a sleeve surrounding the outside of said packer and underlying a portion thereof, a gland acting as a stop for the upper end of the packer and drawing means to move the sleeve upwardly toward said gland to compress the packer into tight sealing engagement with the kelly, a rotatable housing in which said sleeve is vertically movable, said kelly serving as a means to rotate the packer, the sleeve and the rotatable housing, said packer, sleeve, gland and drawing means constituting a removable assembly as a unit, and means to lock or unlock said removable assembly to said rotatable housing.

2. A pressure drilling head of the type adapted to receive a rotary kelly and including a packer, a sleeve surrounding the outside of said packer, and underlying a portion thereof, a gland acting as a stop for the upper end of the packer and drawing means to move the sleeve upwardly toward said gland to compress the packer, a rotatable housing in which said sleeve is vertically movable, said kelly serving as a means to rotate the packer, sleeve and rotatable housing, a fixed housing in which said rotatable housing rotates, said packer, sleeve, gland and drawing means constituting a removable assembly as a unit, and means to lock or unlock said removable assembly to said rotatable housing.

3. A pressure drilling head of the type adapted to receive a rotary kelly and including a fixed housing, a rotatable housing rotatable in the fixed housing, a vertically movable sleeve within the rotatable housing, a packer within the said sleeve, said kelly serving as a means to rotate the packer, sleeve and rotatable housing, means to compress the packer by the upward movement of the sleeve, means to secure the sleeve in the rotatable housing, said sleeve and packer being removable as a unit from the rotatable housing when the securing means is released.
